VACUUM CLEANER

Otto W. Timm, Van Nuys, Calif., assignor to
 Timm Aircraft Corporation, Van Nuys, Calif.,
 a corporation of California

Application September 25, 1944, Serial No. 555,645

22 Claims. (Cl. 183—52)

1

My invention relates to the vacuum cleaner art and, more particularly, to a vacuum cleaner adapted for household or hotel use or the like and having a number of improvements over standard types of such devices.

It is common in the art to provide a vacuum cleaner of the suction type with a motor and a dust collecting chamber enclosed in a housing, the device having supporting runners and adapted to be moved from place to place in operation by a suction hose connected to the suction opening of the device. Such vacuum cleaners commonly are provided with the motor and dust chamber in horizontal axial alignment, which provides a very low construction which is awkward for an operator to pick up, as must frequently be done in moving the device from room to room for operation. It is therefore an object of my present invention to provide a wholly enclosed vacuum cleaner of sufficient height to permit the handle thereof to be grasped by an operator without requiring a substantial stooping movement of the operator, thus relieving the physical effort required to move many of the vacuum cleaners of the prior art. I prefer to accomplish this object by providing an enclosed housing separated by a partition into a vertical motor chamber and a vertical filter chamber, a motor and fan unit being disposed in the motor chamber and a vertical filter bag being disposed in the filter chamber, and this is a further object of the invention.

Vacuum cleaners of the art commonly use a bag of filter fabric, through which dust laden air is drawn by suction, or forced by a blower, to remove the dust and dirt from the air. Such bags must normally be detached frequently from the operating part of the unit and emptied of the dust and dirt collected therein, and it is normally difficult for the ordinary operator to detach the bag from the device without spilling some of the dust therefrom. Furthermore, with enclosed vacuum cleaners in which the bag is normally disposed within an enclosed housing, the bag must necessarily be relatively small in volume, which requires more frequent emptying and is a dirty job at best. It is therefore a further object of my invention to provide an enclosed vacuum cleaner having a dust filtering bag in an enclosed housing, which bag does not have to be removed at frequent intervals due to the fact that the dust filtered from the air passing through the bag is collected in a separate collecting tray which can readily and cleanly be removed independently of the bag from the vacuum cleaner for emptying. I prefer to line such a tray with a disposable liner, so that the dust collected by the tray is deposited in the liner, and so that the liner filled with dust may be disposed of as a unit and a fresh liner substituted therefor, and this is another object of the invention.

2

Still another object of my invention is to provide a vacuum cleaner in which dust and foreign materials are filtered from incoming air on the outside of a suitable filter bag, with means provided for agitating the bag as desired to remove dust therefrom and thus clean the filtering surface.

A further object is to provide such a device in which the filter bag is agitated by agitating mechanism contained within the bag, preferably including an auxiliary electric motor for actuating the agitating mechanism. To accomplish this purpose, the elements of the agitating mechanism, described hereinafter, are of significance.

Another object of the invention is to provide a vacuum cleaner having a filter bag disposed in an enclosed housing, air to be filtered passing through the filter bag, with baffle means provided in the housing to deflect the incoming flow of air which would otherwise impinge directly on the bag, to prevent such direct impingement to increase the life of the bag and to distribute more uniformly the dust laden air over the surface of the bag.

A further object of the invention is to provide a vacuum cleaner having a main motor for drawing air through the device, and an auxiliary motor for agitating a filter bag to remove dust from the filtering surface thereof, electric switch mechanism being provided such that the main and auxiliary motors may be selectively actuated as desired, but designed so that both motors cannot be energized simultaneously.

Still another object of the invention is to provide a vacuum cleaner in which the air filtered by the device, after being filtered, passes in proximity to the motor windings to cool the same.

To insure most efficient operation of a vacuum cleaner, and to prevent undue wear on surfaces to be cleaned, it is common to provide means for varying the suction exerted by the device. Various expedients have been attempted to achieve this result, one of the commonest being to provide some sort of adjustment means, such as a screw arrangement, for adjusting and holding the suction throat of the unit at a desired predetermined height from the surface to be cleaned. Such expedients have not been satisfactory in actual use by unskilled operators, as such operators rarely take the trouble to make the proper adjustments, probably mainly because of the physical effort involved in bending over sufficiently to accomplish it. It is therefore another object of my present invention to provide a simplified and improved means of controlling the suction of a vacuum cleaner. I prefer to accomplish this by supplying an auxiliary valve member, conveniently located on the vacuum cleaner, whereby the operator may control an auxiliary opening by-passing and in parallel with the suction opening of the device. Furthermore, I prefer to pro-

vide such a mechanism with means whereby if, for any reason, the suction exerted by the main suction opening exceeds a predetermined value, the auxiliary opening will automatically open to prevent the suction exerted by the main suction opening from rising substantially above such value or above a predetermined adjustable limit.

A further object of the invention is to provide a novel connecting means for connecting a hose or pipe with a housing so as to form a fluid seal therebetween and yet permit substantial transverse relative movement therebetween. I prefer to accomplish this by providing what in effect is a ball-and-socket joint, at least one of the elements thereof being of resilient material such as rubber, the socket being retained in a suitable opening in the housing and the ball providing a tubular connection for a hose or pipe nipple. Such a construction is of particular utility in vacuum cleaners for connecting a suction hose to the vacuum cleaner, but, obviously, has other uses within the spirit of the invention.

Still another object of the invention is to provide a novel reel construction for holding a power cord, or cable, such that the cord may be unwound to any desired portion of its length and such that the reel may be actuated to rewind the cord thereon. Such a construction, obviously, is of particular utility in connection with a vacuum cleaner such as described above, and it is also an object of the invention to provide such a reel device in a vacuum cleaner, but I do not desire to be limited thereto.

Other objects lie in the relative positioning of the features pointed out hereinabove for compactness, ease of assembly and repair, and ease of operation.

Additional objects will also be evident from the following specification and the drawings, which are for the purpose of illustration only, and in which:

Fig. 1 is a longitudinal vertical cross-sectional view taken through my vacuum cleaner.

Fig. 2 is a vertical cross-sectional view taken on the line 2—2 of Fig. 1.

Fig. 3 is a top view of the device shown in Fig. 1, with the cap member removed.

Fig. 4 is an enlarged fragmentary cross-sectional view taken on the line 4—4 of Fig. 1.

Fig. 5 is an enlarged plan view of the control knob of the auxiliary valve mechanism of the device.

Fig. 6 is a vertical cross-sectional view of the device shown in Fig. 5.

Fig. 7 is an enlarged cross-sectional view of the hose connector of my invention.

Fig. 8 is a fragmentary cross-sectional view taken on the line 8—8 of Fig. 7.

Fig. 9 is a view similar to Fig. 7 of an alternative embodiment of the hose connector.

Fig. 10 is an enlarged cross-sectional view, similar to Fig. 2, of an alternative embodiment of the filter bag agitating means.

Fig. 11 is a view similar to Fig. 10 of a further alternative embodiment of the filter bag agitating means.

Fig. 12 is an end view of the deflector baffle of the invention.

Referring to the drawings, I show a housing 15 having side walls 16 and 17 and a bottom wall 18, the housing being divided by a vertical partition wall 19 into a motor chamber 20 and a filter chamber 21. The housing 15 also has a front wall 23 and a back wall 24 which round into the side walls 16 and 17 as illustrated in

Fig. 3, the front wall, back wall, and side walls converging as they extend upwardly to form a rounded top portion 25 of the housing. The rounded top portion 25 of the housing 15 is provided at its upper end with a flat flange plate 26 provided with an opening 27 communicating with the motor chamber 20 and provided with an opening 28 communicating with the filter chamber 21. As will be noted, the openings 27 and 28 are separated by the lateral partition wall 19. Secured to the flange plate 26, as by bolts 30, is a convex cap member 31 which is sealed relative to the flange plate by a peripheral sealing ring 32 carried in a suitable groove formed in the cap member, the sealing ring 32 preferably being formed of rubber or other resilient material. As illustrated in Figs. 1 and 2, the cap member 31 provides an external configuration which is a continuation of the configuration of the rounded top portion 25 of the housing 15, and defines an upper chamber 33 providing communication between the opening 27 and 28, the cap member also being provided with a suitable handle 34 by which the housing may be carried from place to place.

Formed in the bottom wall 18 of the housing 15 beneath the motor chamber 20 is a bottom opening 35 of only slightly less cross-sectional area than the lower portion of the motor chamber, which is normally closed by a closure plate 36 fastened to the bottom wall 18 by suitable screws or otherwise. Also secured to the bottom wall 18 of the housing 15 is a pair of runners 37 and 38 which provide a support for the housing 15 and allow it to be readily slid on a floor or other supporting surface. In the back wall 24 of the housing 15, adjacent the bottom wall 18, is provided a power cord opening 39, and directly thereabove is disposed a discharge opening 41, the openings 39 and 41 preferably being circular in form.

Disposed in the motor chamber 20 is an electric motor 42, the motor being in vertical position as shown and having a drive shaft 43 extending upwardly therefrom into the motor chamber. While the motor 42 is preferably vertically disposed in the motor chamber 20 to provide a compact unit having an external configuration which is convenient to handle and pleasing to the eye, which are advantages of the invention, still it is possible to mount such a motor horizontally in the motor chamber while obtaining the other advantages of the invention, and consequently both types of motor mountings are within the spirit of my invention. The motor 42 is supported on a resilient supporting plate 44, preferably formed of rubber or other resilient material, which in turn is supported by a vertical pin 45 which extends into and is supported by a vertical sleeve member 47 provided at its lower end with an annular flange 48, which in turn is suitably secured to the upper face of the closure plate 36, by suitable screws or otherwise. As illustrated in Fig. 4, the periphery of the flange 48 is provided with a pair of notches 49 and 50 engaged by dogs 51 and 52, respectively, formed on arcuate detent members 53 and 54, respectively, the detent members being held in engagement with the annular flange 48 by tension springs 55 and 56 exerting a very light tension between the detent members. The detent members 53 and 54 are secured by pivot pins 58 and 59, respectively, to a circular lower plate 60 of a reel device 61. The reel device 61 also includes an upper plate 62 generally similar in configuration to the lower

plate 60, having a depending annular coil flange 63 suitably secured to the lower plate 60, as by screws or otherwise, to form the reel device. Provided within the reel device 61 is a flat spiral spring 64, one end of which is riveted or otherwise secured to the inner wall of the coil flange 63 and the other end of which is riveted or otherwise suitably secured to the outer wall of the vertical sleeve member 47. An electric cable 66 passes through the power cord opening 39 and is wound on the outer periphery of the coil flange 63 and suitably secured thereto while the spiral spring 64 is expanded to substantially its expansion limits so that by pulling the end of the cable 66 the reel device 61 will rotate on the vertical sleeve member 47 to permit withdrawal of the cable. Such rotation is in the direction of the arrow 67, shown in Fig. 4, and, as will be understood, the dogs 51 and 52 move out of their notches 49 and 50 and continue to pass thereover during rotation of the reel device until the cable 66 is released, at which time the spiral spring 64 reverses the direction of rotation of the reel device until the dogs fall into the nearest notches, preventing further counterclockwise rotation of the reel device relative to the vertical sleeve member 47, as the same is shown in Fig. 4. By imparting a sudden slight jerk to the cable 66, the reel device 61 first rotates slightly in the direction of the arrow 67, and the spiral spring 64 almost immediately reverses the direction of movement of the reel device, tending to reel in the cable. As the detent members 53 and 54 are eccentrically pivoted on their pins 58 and 59, the sudden rotation of the reel device 61 in a counterclockwise direction rotates the detent members on their pins, by centrifugal force and against the action of the springs 55 and 56, outwardly away from the periphery of the flange 48 so that the dogs 51 and 52 will not engage in the notches 49 and 50, which rotation continues so long as the cable is allowed to freely wind onto the reel device. If the running in of the cable is slowed down, by hand or otherwise, the springs 55 and 56 operate to draw the detent members 53 and 54 into engagement with the periphery of the flange 48 to engage the notches 49 and 50, thus stopping further winding of the reel device by the action of the spiral spring 64. This specific reel device construction is also a valuable feature of the invention. The construction just described provides a convenient location for the reel device 61 and provides a resilient seat for the electric motor 42, which are further advantages of the invention.

Suitably fixed on the upper end of the electric motor 42 is a circular bracket plate 68 provided with a plurality of openings 69 therethrough communicating with the interior of the motor so that air can pass through said openings and through the motor to cool the same, passing out of lower openings 70 formed in the motor housing. The bracket plate 68 is provided with a vertical annular rim 72 having an annular groove 73, arcuate in cross section, in its outer face which receives an annular sealing ring 74, preferably formed of rubber or other resilient material, which in turn is retained in an annular groove 75 formed in a flange 76 projecting into the motor chamber 20. It will be apparent that the sealing ring 74 forms a fluid-tight seal between the bracket plate 68 and the flange 66 and also serves to cushion vibration of the electric motor 42, such vibration also being cushioned by the resilient supporting plate 44.

5 Mounted on the annular rim 72 is an enclosed cap member 78 provided with a central opening 79 in the top thereof, there being fan means 80 mounted within the cap member. The fan means 80 includes a plurality of rotatable fan blades 81 mounted on the drive shaft 43 of the electric motor 42, and a plurality of stationary baffles 83 mounted by suitable brackets on the annular rim 72 so as to cooperate with the fan blades to cause 10 air to pass downwardly through the fan means and the electric motor in response to rotation of the drive shaft 43. A conical filter element 84 is mounted on the top of the cap member 78, such filter element being of any type well known 15 in the art and formed of fabric or other material such that it is adapted to filter air passing from the motor chamber 20 into the cap member through the central opening 79, and it is to be understood that any equivalent filter element is 20 within the spirit of the invention. It is desirable in most installations to provide such a filter element 84, or the equivalent thereof, to prevent any fine dust from entering the electric motor 42 or from being exhausted back into the atmosphere. 25 Formed in the top of the upper plate 62 of the reel device 61 is a pair of concentric annular grooves containing concentric electrical collecting rings 85 and 86, each of which is electrically connected to one of the wires of the electric cable 66, as is well known in the art, the collecting rings 30 being electrically engaged by stationary brush contacts 87 and 88, respectively, the brush contacts being electrically connected by wires 90 and 91, respectively. The wire 90 is electrically connected to both the electric motor 42 and an auxiliary electric motor 92, to be described hereinafter, and the wire 91 is connected to an electric switch 93 mounted on the inner wall of the rounded top portion 25 of the housing 15 and having a switch lever 94 projecting from the housing so as to be 35 readily accessible to an operator. One throw-contact of the electric switch 93, as is well known in the art, is connected by a wire 96 with the other side of the electric motor 42, and another throw-contact of the switch 93 is connected by a wire 97 with the other side of the auxiliary electric motor 92, as is well known in the art. As will be understood, movement of the switch lever 45 94, when the electric cable 66 is connected to a power source, will alternatively energize the electric motor 42 or the auxiliary electric motor 92, depending upon the position to which the switch lever has been moved by the operator, but both 50 motors cannot be actuated at the same time, and this is an important feature of the invention. 55 When the switch lever 94 is in the central or neutral position shown, neither of the motors 42 or 92 is energized.

Disposed in the filter chamber 21 is a filter bag element 99 comprising the filtering means of the 60 invention, the bag element being formed of a suitable filter material such as, for example, cloth or the like. The filter bag 99 is generally rectangular in horizontal cross section, although any 65 other form may be used as desired, and includes side walls 100 and a closed bottom wall 101. The filter bag element 99 is suspended in the filter chamber 21 by the top of the side walls 100 thereof being passed over a peripheral sealing ring 102, 70 preferably formed of rubber or other resilient material, which is clamped between the inner face of the opening 28 and a depending flange 103 formed on a supporting plate 104, which in turn is supported on and suitably secured to the flat flange plate 26, as by screws or otherwise. The 75

auxiliary electric motor 92 is suitably secured to the lower side of the supporting plate 104 and extends downwardly into the filter bag 99, thus occupying no space in the upper chamber 33 of the cap member 31 and being conveniently located for assembly or replacement. The supporting plate 104 is provided with a conduit opening 106 through which the wires 90 and 97 extend to the auxiliary electric motor 92, and is also provided with a main opening 107 which provides communication between the interior of the filter bag 99 and the upper chamber 33 in the cap member 31.

Disposed within the filter bag 99 adjacent the corners thereof are four vertical frame members 108, the tops of which are connected rigidly to the inner wall of the depending flange 103 of the supporting plate 104, as by screws or otherwise, adjacent vertical frame members being connected by horizontal frame elements 109 which serve to brace the frame members and for a further function to be described hereinafter. As will be noted, the frame members 108 and the frame elements 109 are disposed adjacent the inner wall of the side walls 100 of the filter bag 99, for a purpose also to be described hereinafter.

The auxiliary motor 92 is provided with a bracket arm 111 which journals for rotation a stub shaft 112 on which is mounted a gear wheel 113 which meshes with a pinion 114 mounted on a drive shaft 115 of the auxiliary motor. The gear wheel 113 is provided with a pin 117 mounted eccentrically thereon relative to the center of rotation of the gear wheel, on which pin is mounted for relative rotational movement the upper end of an actuating arm 118, on the lower end of which is connected a frame element 119 providing a rectangular frame 120 of substantially the same configuration as the bottom wall 101 of the filter bag 99 and secured thereto by an adhesive or by other suitable means, the frame element being connected to the actuating arm by a socket 121. As will be noted, the actuating arm 118 is so dimensioned that when the gear wheel 113 is in the position illustrated, in which the pin 117 is below and vertically aligned with the axis of the stub shaft 112, the filter bag 99 will be wholly extended. The auxiliary motor 92 and the actuating arm 118 and associated parts constitute an agitating means of the invention.

Removably disposed beneath the filter bag 99 in the filter chamber 21 is a removable tray 122 which is generally rectangular in shape and which fits into a rectangular opening 123 formed in the front wall 23 of the housing 15 adjacent the bottom wall 18 thereof, the tray being supported by the walls of the rectangular opening and by supporting runners 124 and 125 suitably fixed, as by screws, to the upper face of the bottom wall 18 of the housing 15. The tray 122 is guided into and out of the housing 15 by guide flanges 126 and 127 formed on the side walls 16 and 17, respectively, as illustrated in Fig. 2, the guide flanges being provided with longitudinal grooves containing longitudinal sealing strips 128 and 129, respectively, preferably formed of rubber or other resilient material adapted to form a seal between the tray 122 and the side walls 16 and 17. In the wall of the opening 123, in a suitable groove provided therein, is disposed a peripheral sealing strip 131, also preferably formed of rubber or other resilient material, which forms a seal with the sides and bottom of the movable tray 122.

As will be noted from Fig. 1, the removable tray 122 is provided with a convex front wall 132, of the same general configuration as the

lower portion of the front wall 23 of the housing 15, providing at its lower end a shoulder 133 which engages the housing when the removable tray is in its inserted position as illustrated in Fig. 1, the shoulder snapping beneath a spring clip 134 secured to the bottom wall 18, to retain the removable tray in the position illustrated. The front wall 132 of the tray 122 is provided with a handle member 135 to facilitate insertion or removal of the tray, and the top of the tray is provided with a transverse bar 136 between the sides of the tray and provided with a groove having a sealing strip 137 therein, also preferably formed of rubber or other resilient material. As will be understood, the sealing strips 128, 129, 131, and 137 are designed to prevent leakage of air into the filter chamber 21 around the removable tray 122 and to seal dust collected in the filter chamber 21 against leakage from the housing 15. As illustrated in Figs. 1 and 2, I prefer to line the removable tray 122 with a liner 139 of the same configuration, the liner being formed of disposal material, such as paper or the like, so that when it is full of dust or other waste material deposited therein, it may be disposed of as a unit. As illustrated in Fig. 1, the front wall 23 of the housing 15 has a reentrant horizontal wall 140, the bottom of which is engaged by the sealing strip 137, and to the top of which is secured a deflector member 141 constituting a baffle means of the invention.

Formed in the front wall 23 of the housing 15 in front of the deflector member 141 is a suction opening 142 having hose connector means 143 disposed therein, which is shown in detail in Figs. 7 and 8. The hose connector means 143 includes a collar element 145 and an insert element 146 retained in the collar element. The collar element 145 is generally tubular in form, having a pair of annular end flanges 147 and 148 which may be expanded to snap the collar element into the suction opening 142, the collar element being formed of rubber or other resilient material. The collar element is also provided with a bore 149 which is concave in longitudinal cross section and which snugly receives a convex outer face 150 of the insert element 146, which is preferably formed of metal or plastic or other non-resilient material, the outer face 150 being provided with a longitudinal groove 151 adapted to receive a portion of the collar element 145 squeezed into the groove. As will be understood, the groove 151 provides means tending to retain the collar element 145 and insert element 146 in any relative position to which they may be moved. The insert element 146 is also provided with a tubular bore 154 into which projects a round locking pin 155 suitably retained in a radial opening formed in the insert element. As illustrated in Fig. 7, the locking pin 155 is adapted to fit into a bayonet slot 156 formed in a conventional nipple 157 used for connecting a flexible hose (not shown) to the housing 15, as is well-known in the art. Due to the mating relation of the concave bore 149 and the convex outer face 150, in effect a ball-and-socket joint arrangement is provided between the collar element 145 and the insert element 146, allowing the insert element to be rotated trans-axially relative to the collar element so as to accommodate different positions of the nipple 157 relative to the housing 15 as may be desired, and due to the fact that the collar element is formed of rubber, a fluid-tight

seal is provided between it and the insert element.

An alternative form of hose connector means is illustrated in Fig. 9, in which an outer element 159 and an inner element 160 perform functions similar to the collar element 145 and the insert element 146, respectively, the construction differing somewhat from the preferred embodiment in the structural details. In this form, a front wall 161, generally similar to the front wall 23, is provided with a suction opening 162 bounded on one side by an annular flange 163 formed on the front wall 161 and bounded on the other side by a flange 164 formed on an annular clamping member 165 suitably secured to the front wall 161. Between the flanges 163 and 164 is retained the annular outer element 159, which is generally tubular in shape but is provided with a concave bore 166 which receives a convex outer face 167 provided on the inner element 160. A groove, similar to the groove 151, may be provided between the inner and outer elements 160 and 159, respectively, if desired, and the inner element is provided with a round locking pin 168 retained in a suitable opening in the inner element and projecting into a tubular bore 169 thereof to provide means for locking a conventional nipple 170, similar to the nipple 151, relative to the inner element.

Also carried by the front wall 23 of the housing 15, as best illustrated in Figs. 1, 5, and 6, is an auxiliary valve means 172. The auxiliary valve means 172 may be of any desired form providing an orifice through the wall 23 of the housing 15 normally closed by a flapper plate which is spring loaded under variable tension, and I do not intend to be limited to the specific construction illustrated and described as follows. The auxiliary valve means 172 includes a valve opening 173 formed in the front wall 23 of the housing 15, the outer portion of the opening being provided with a counterbore 174. The opening 173 is normally closed by a flapper plate 175 adapted to move out of engagement with the front wall 23, being guided in such movement by a guide pin 176 secured in a suitable opening in the front wall. The flapper plate 175 has a square opening 178 therein aligned with the axis of the opening 173, which retains a square shank 179 of a stud 180, the head of which engages the flapper plate, the stud being provided with a round threaded portion 181 which passes outwardly through the opening 173. Threaded on the stud 180 is a control knob 182, there being a compression spring 183 disposed between the control knob and the front plate 23 and seating in the counterbore 174. The compression spring 183 is such that when in the position illustrated in Fig. 6 there will be substantially no compression thereon, and the flapper plate 175 may move readily away from the front wall 23 to permit the passage of air through the opening 173, but being so constructed that upon screwing the control knob 182 down upon the stud 180, the compression of the compression spring may be increased to require greater force to move the flapper plate away from the front wall. An indicating arrow 184 may be provided on the exterior of the front wall 23, as illustrated in Fig. 5, and indicia 185 may be provided on the periphery of the control knob 182 so as to register with the indicating arrow to indicate the degree of compression of the compression spring 183, so as to permit simple visual setting of the auxiliary valve means.

As best illustrated in Figs. 2 and 3, a pair of longitudinal band elements 187 and 188 are horizontally disposed around the periphery of the housing 15, the band element 187 comprising a flat plate 189 suitably secured to the side wall 16 as by screws or otherwise, having edges 190 and 191 which are bent back toward each other to clamp a resilient projecting bumper strip 192 therebetween. The band element 188 is formed similarly to the band element 187, and the two band elements provide bumper means to prevent the housing 15 from being scratched by collision with walls, furniture, and the like, or vice versa.

Fig. 10 illustrates an alternative form of agitating means for use in the filter bag element 99, parts thereof corresponding to similar parts shown in Fig. 2 being identified by the same numerals with the suffix "a" thereafter. In this form, an actuating arm 118a has secured thereon intermediate its ends a sleeve 194 to which is bonded a resilient circular diaphragm 195, preferably formed of rubber or other resilient material, which in turn is retained at its outer edge by clip members 196 which are in turn secured to post members 108a. Otherwise, the construction is as illustrated in Fig. 2. In this alternative construction illustrated in Fig. 10, reciprocation of the actuating arm 118a and lateral movement of its upper end cause reciprocation and lateral movement of the lower end thereof so as to provide an exaggerated lateral shaking action to the filter bag element 99a. The form illustrated in Fig. 11 accomplishes substantially the same function as that illustrated in Fig. 10, but provides alternative mechanical means therefor, like parts being indicated by the same numeral with the suffix "b" thereafter. In the form shown in Fig. 11, to the socket 121b is pivoted, as by a pivot pin 197, a short link 198, the other end of which is pivoted by a pivot pin 199 to an extension 200 of one of the post members 108b. This construction insures substantial lateral movement of the filter bag element 99b in response to reciprocation of the actuating arm 118b.

As illustrated in Fig. 1, the discharge opening 41 is provided with hose connector means 202 generally similar to the hose connector means 143, to permit a discharge hose nipple 203 to be flexibly connected to the housing 15 in the event it is desired to use the device as a blower.

In the forms illustrated, the auxiliary motor 92 and the mechanism connected thereto for agitating the filter bag element 99 are contained within the filter bag element to conserve space, which is an object of the invention, the air to be cleaned passing from the outside of the filter bag element therethrough into the inside thereof. It will be apparent to those skilled in the art, however, that dust could be collected on the inside of a filter bag and the motor and actuating mechanism disposed on the outside thereof without departing from the spirit of the invention so far as the other features of novelty are concerned.

In operation, the preferred embodiment illustrated in Fig. 1 is assembled as illustrated. The electric motor 42 is energized by suitable actuation of the electric switch 93, which rotates the rotatable fan blades 81 to cause air to flow through the nipple 151 and the hose connector means 143 into the filter chamber 21. The flow of such air is deflected laterally and upwardly by the deflector member 141 so that it will not impinge directly upon the filter bag element 99 as it issues from the hose connector means 143 into the filter chamber. The action of the deflector mem-

ber 141 is important in the operation of the device, as it would be undesirable to have a column of incoming air traveling at high velocity impinge directly upon the filter bag element 99, which would tend to drive dust particles through the filter bag element and would cause an inordinate amount of wear of the fabric from which the same is formed.

As the dust laden air flows around in and upwardly in the filter chamber 21, a large percentage of the dust suspended therein settles by gravity into the liner 139 of the removable tray 122, where it is collected. The air then passes through the filter bag element 99 and upwardly through the interior thereof, passage of the air through the filter bag element filtering substantially all remaining dust particles therefrom, which dust particles collect upon the outer surface of the filter bag element. The air moves from the interior of the filter bag element 99 through the main opening 167 of the supporting plate 104 into the upper chamber 33; through which it passes, passing downwardly through the opening 27 into the motor chamber 20 and being drawn by the fan means 80 through the conical filter element 84 which effectively removes the last traces of dust particles from the air. The air then flows through the fan means 80 and through the openings 69 in the circular bracket plate 68 into the electric motor 42, cooling the same, and discharging therefrom through the lower openings 70 thereof and finally passing outwardly through the hose connector means 202 to exhaust into the atmosphere.

If, for any reason, suction on the filter chamber 21 is increased by reduction of the effective available area of the opening provided by an appliance connected to the nipple 157, which frequently occurs if a vacuum cleaner attachment is positioned against or in very close proximity to a surface being cleaned, the increase in suction on the filter chamber operates to open the auxiliary valve means 172. Such suction on the flapper plate 175 against the action of the compression spring 183 tends to move the flapper plate 175 inwardly to open the opening 173 to the filter chamber. This permits a flow of air directly into the filter chamber 21 through the opening 173, which flow of air is in parallel with the air flowing through the hose connector means 143, and reduces the suction exerted by the device through the nipple 157, preventing injury or undue wear on the fabric being treated by the vacuum cleaner attachment connected to the nipple 157, as described. The auxiliary valve means 172 thus serves as a safety feature preventing overloading and overheating of the motor 42, and preventing damage to fine fabrics which cannot safely be exposed to a high degree of suction. This permits use of a motor 42 and fan means 80 capable of creating a far greater suction effect than is possible with present day cleaners not equipped with such safety feature, and is desirable so as to afford increased suction which is available if desired but normally inoperative. As indicated above, by rotating the control knob 182, action of the auxiliary valve means 172 may be controlled within reasonably accurate limits to provide the desired degree of suction, and no more, on the nipple 157.

Periodically the external surface of the filter bag element 99 should be cleaned of the layer of dust which accumulates thereon, although it is to be noted that due to the gravity separation and settling of the dust into the removable tray

22, by reason of the positioning of the parts, the frequency of cleaning of the filter bag element is materially reduced. Cleaning of the filter bag element 99 is accomplished by operating the lever 5 94 of the electric switch 93 so as to energize the auxiliary electric motor 92. This rotates the pinion 114, which in turn rotates the gear wheel 113, causing reciprocal movement of the actuating arm 118. Reciprocal movement of the actuating arm 118 flexes the side walls 100, causing dust adhering thereto to fall downwardly through the filter chamber 21 into the removable tray 122, thus freeing the external surface of the filter bag element 99 of dust collecting thereon. Such reciprocal movement of the actuating arm 118 also causes the inner surface of the side walls 100 to strike against the frame members 108 and the frame elements 109 to provide a beating action further tending to remove dust from the exterior surface of the side walls 100. This cleaning action is quite efficient, and only a few seconds of operation of the auxiliary electric motor 92 is sufficient to remove all surplus dust from the exterior of the side walls 100 of the filter bag element 99. The electric switch 93 may then again be operated to energize the electric motor 42 to continue the suction cleaning operation.

In the alternative embodiment illustrated in Figs. 10 and 11, a more violent agitation of the filter bag element than is obtained in the preferred embodiment illustrated in the preceding figures is accomplished. In the construction illustrated in Fig. 10, this increased agitation is produced by the connection of the actuating arm 35 118a to the frame members 108a by the circular diaphragm 195, which gives an increased lateral movement to the rectangular frame 120a upon rotation of the gear wheel 113a. Similarly, in the construction illustrated in Fig. 11, the connection of the actuating arm 118b to the frame members 108b by the link 198 provides a positive and marked lateral movement to the rectangular frame 120b upon rotation of the gear 113b. As will be apparent, the alternative embodiments 40 illustrated in Figs. 10 and 11 provide a more violent agitation of the filter bag element than in the preferred embodiment, thus reducing the time interval required to clean the wall of the filter bag element of dust accumulated thereon. 45 This feature is of value primarily where the time of operation of the device is an element, as in hotel use or other commercial use. As will be apparent, however, such increased agitation increases wear on the filter bag element substantially, and consequently for ordinary home use I prefer to provide the more gentle action described in connection with the preferred embodiment 50 above.

It will be apparent to those skilled in the art 55 that many of the elements of my device, as illustrated and described hereinabove, may be replaced by other elements having substantially the same mode of operation without departing from the spirit of my invention, and consequently I do not desire to be limited to the specific forms 60 illustrated and described, but desire to be afforded the full scope of the following claims.

I claim as my invention:

1. In a vacuum cleaner, the combination of: an enclosed housing internally divided by partition means into a motor chamber and a filter chamber, said housing having a suction opening in said filter chamber and having a discharge opening in said motor chamber; an electric motor 65 disposed in said motor chamber; filter means in

10
said filter chamber adapted to filter dust from air drawn through said filter means from said suction opening, said filter means depending into alignment with said suction opening; fan means associated with said motor and adapted to be actuated thereby to draw air through said suction opening into said filter chamber, through said filter means to filter dust therefrom, and through said motor chamber and out said discharge opening; and baffle means disposed in said filter chamber between said suction opening and said filter means for deflecting air entering said filter chamber through said suction opening from direct impingement on said filter means, said deflection being lateral and upward around said filter means.

2. In a vacuum cleaner, the combination of: an enclosed housing internally divided by partition means into a motor chamber and a filter chamber, said housing having a suction opening in said filter chamber and having a discharge opening in said motor chamber; an electric motor disposed in said motor chamber; filter bag means in said filter chamber adapted to filter dust from air drawn through said filter means from said suction opening; fan means associated with said motor and adapted to be actuated thereby to draw air through said suction opening into said filter chamber, inwardly through said filter means to filter bag dust therefrom, and through said motor chamber and out said discharge opening; and a reel device in said motor chamber below said motor supporting said motor and adapted to carry on electric cord for energizing said motor.

3. In a vacuum cleaner, the combination of: an enclosed housing internally divided by partition means into a motor chamber and a filter chamber, said housing having a suction opening in said filter chamber and having a discharge opening in said motor chamber; a main electric motor disposed in said motor chamber; filter means suspended from said partition means and depending into said filter chamber and adapted to filter dust from air drawn through said filter means from said suction opening; an auxiliary electric motor supported on said partition means and extending into said filter means; means connecting said auxiliary motor to said filter means so that energization of said auxiliary motor agitates said filter means to dislodge dust therefrom; and fan means associated with said electric motor and adapted to be actuated thereby to draw air through said suction opening into said filter chamber, through said filter means to filter dust therefrom, and through said motor chamber and out said discharge opening.

4. In a vacuum cleaner, the combination of: an enclosed housing internally divided by partition means into a motor chamber and a filter chamber, said housing having a suction opening in said filter chamber and having a discharge opening in said motor chamber; an electric motor disposed in said motor chamber; filter means in said filter chamber adapted to filter dust from air drawn through said filter means from said suction opening; an auxiliary electric motor; means connecting said auxiliary motor to said filter means so that energization of said auxiliary motor agitates said filter means to dislodge dust therefrom; a single switch connected between a source of electric power and both of said motors so that either of said motors can be selectively energized but so that both of said motors cannot be energized simultaneously; and fan means associated with said motor and adapted to be actuated

thereby to draw air through said suction opening into said filter chamber, through said filter means to filter dust therefrom, and through said motor chamber and out said discharge opening.

- 5 5. In a vacuum cleaner, the combination of:
an enclosed housing internally divided by parti-
tion means into a motor chamber and a filter
chamber, said housing having a suction opening
in said filter chamber and having a discharge
10 opening in said motor chamber; an electric
motor disposed in said motor chamber; filter
means in said filter chamber adapted to filter
dust from air drawn through said filter means
from said suction opening; an auxiliary electric
15 motor; means connecting said auxiliary motor
to said filter means so that energization of said
auxiliary motor agitates said filter means to dis-
lodge dust therefrom; a single switch mounted
20 in said housing and operable from the exterior
thereof and connected between a source of elec-
tric power and both of said motors so that either
of said motors can be selectively energized but
so that both of said motors cannot be energized
25 simultaneously; and fan means associated with
said motor and adapted to be actuated thereby
to draw air through said suction opening into
said filter chamber, through said filter means to
filter dust therefrom, and through said motor
30 chamber and out said discharge opening.

30 6. In a vacuum cleaner, the combination of:
an enclosed housing internally divided by parti-
tion means into a motor chamber and a filter
chamber, said housing having a suction opening
in said filter chamber and having a discharge
35 opening in said motor chamber; an electric motor
in said motor chamber; filter means in said filter
chamber adapted to filter dust from air drawn therethrough from said suction opening, said
filter means including a flaccid bag of filter
40 material suspended loosely within said housing
and depending into said filter chamber; an ele-
ment connected to the lower closed end of said
bag; an auxiliary electric motor in said bag;
means for connecting said auxiliary motor to
45 said element so that energization of said aux-
iliary motor agitates said element and said bag
to dislodge dust from said bag; and fan means
associated with said motor and adapted to be
actuated thereby to draw air through said suction
50 opening into said filter chamber, through said
filter means to filter dust therefrom, and through
said motor chamber and out said discharge
opening.

7. In a vacuum cleaner, the combination of:
55 an enclosed housing internally divided by parti-
tion means into a motor chamber and a filter
chamber, said housing having a suction opening
in said filter chamber and having a discharge
opening in said motor chamber; an electric motor
60 in said motor chamber; filter means in said filter
chamber adapted to filter dust from air drawn therethrough from said suction opening, said
filter means including a flaccid bag of filter ma-
terial suspended loosely within said housing and
65 depending into said filter chamber; a plurality of
vertical frame members within said bag and ad-
jacent the inner wall of said bag; an element
connected to the lower closed end of said bag; an
auxiliary electric motor in said bag; means con-
70 necting said auxiliary motor to said element so
that energization of said auxiliary motor agitates
said element and said bag and causes said bag to
strike said frame members to dislodge dust from
said bag; and fan means associated with said
75 motor and adapted to be actuated thereby to

15

draw air through said suction opening into said filter chamber, through said filter means to filter dust therefrom, and through said motor chamber and out said discharge opening.

8. In a vacuum cleaner, the combination of: a housing having an opening in one end thereof for inserting a motor thereinto; a partition in said housing and supported thereby, said partition dividing said housing into a first chamber adjacent said opening and a second chamber remote therefrom, said partition having an aperture communicating between said chambers; a first port communicating with said first chamber; a second port communicating with said second chamber; an electric motor in said first chamber and engaging said partition; fan means connected to said motor and adapted to be driven thereby for moving air between said ports; a removable cover member closing said opening; and a reel device in said first chamber between said motor and said cover member and adapted to support said motor, said reel device being adapted to carry an electric cord for energizing said motor.

9. In a vacuum cleaner, the combination of: a housing having an opening in one end thereof for inserting a motor thereinto; a partition in said housing and supported thereby, said partition dividing said housing into a first chamber adjacent said opening and a second chamber remote therefrom, said partition having an aperture communicating between said chambers; a first port communicating with said first chamber; a second port communicating with said second chamber; an electric motor in said first chamber and engaging said partition; fan means connected to said motor and adapted to be driven thereby for moving air between said ports; sealing means adapted to form a fluid-tight seal between said motor and said partition around said aperture; a removable cover member closing said opening; and a reel device in said first chamber between said motor and said cover member and adapted to support said motor, said reel device being adapted to carry an electric cord for energizing said motor.

10. In a vacuum cleaner, the combination of: a housing internally divided by partition means into a motor chamber and a filter chamber, said housing having a suction opening in said filter chamber and having a discharge opening in said motor chamber, and having an aperture in the bottom of said motor chamber through which an electric motor can be inserted into said motor chamber; an electric motor vertically disposed in said motor chamber; a removable closure member attached to said housing so as to close said aperture, said closure member supporting said motor; filter means depending into said filter chamber and adapted to filter dust from air drawn through said filter means from said suction opening; agitating means connected to said filter means so that energization of said agitating means agitates said filter means to dislodge dust therefrom; and fan means associated with said motor for moving air between said suction opening and said discharge opening through said filter means.

11. In a vacuum cleaner, the combination of: a housing internally divided by partition means into a motor chamber and a filter chamber, said housing having a suction opening in said filter chamber and having a discharge opening in said motor chamber, and having an aperture in the bottom of said motor chamber through which an electric motor can be inserted into said motor chamber; an electric motor vertically disposed

16

in said motor chamber; a removable closure member attached to said housing so as to close said aperture and operatively connected to said electric motor so as to support the same in said motor chamber; filter bag means depending into said filter chamber and adapted to filter dust from air drawn through said filter means from said suction opening; agitating means connected to said filter bag means within the same so that energization of said agitating means agitates said filter means to dislodge dust therefrom; and fan means associated with said motor for moving air between said suction opening and said discharge opening through said filter means.

12. In a vacuum cleaner, the combination of: a housing internally divided by partition means into a motor chamber and a filter chamber, said housing having a suction opening in said filter chamber and having a discharge opening in said motor chamber, said partition means including a substantially horizontal stationary plate disposed over said filter chamber and having an aperture therein; an electric motor and fan unit vertically disposed in said motor chamber; filter bag means suspended from said plate and extending into said filter chamber with its upper open end aligned with said aperture; means for forming an air seal between the upper end of said filter bag means and said plate; and agitating means disposed wholly within said filter bag means and adapted to agitate said filter bag means so as to dislodge dust therefrom.

13. In a device of the character described, the combination of: a housing having an inlet opening and a discharge opening; filter bag means in said housing between said openings and adapted to filter solid particles from fluid passing therethrough between said openings; impelling means for drawing fluid into said housing through said inlet opening, causing such fluid to pass through said filter bag means, and to discharge it from said housing through said discharge opening; agitating means disposed within and connected to said filter bag means and operable to agitate said filter bag means to dislodge such particles therefrom; a first power-operated means for actuating said impelling means; a second power-operated means for actuating said agitating means; and manually operable means for selectively energizing said first and second power-operated means.

14. In a device of the character described, the combination of: a housing having an inlet opening and a discharge opening; filter means in said housing between said openings and adapted to filter solid particles from fluid passing therethrough between said openings; impelling means for drawing fluid into said housing through said inlet opening, causing such fluid to pass through said filter means, and to discharge it from said housing through said discharge opening; a first electric motor for actuating said impelling means; agitating means connected to said filter means and operable to agitate said filter means to dislodge such particles therefrom; a second electric motor for actuating said agitating means; and energizing means for only alternatively energizing said motors.

15. In a device of the character described, the combination of: a housing having a rounded top; a vertical partition in said housing extending upwardly therein to define a motor chamber on one side thereof and a filter chamber on the other side thereof, said rounded top providing a curved air passage between said chambers; a

motor and fan unit in said motor chamber; and filter means in said filter chamber.

16. In a device of the character described, the combination of: a housing having a rounded top; a vertical partition in said housing extending upwardly therein to define a motor chamber on one side thereof and a filter chamber on the other side thereof, said rounded top providing an air-directing passage of substantially semicircular cross section between said chambers having a curved upper wall adapted to guide the passage of air between said chambers; a motor and fan unit in said motor chamber; and filter means in said filter chamber.

17. In a device of the character described, the combination of: a housing; a vertical partition in said housing defining a motor chamber on one side thereof and a filter chamber on the other side thereof; a first wall disposed in said motor chamber and having a motor opening therein; an electric motor unit in said motor chamber; first resilient sealing means between said unit and said first wall; a second wall in said filter chamber and having a filter opening therein, said second wall being rigidly secured relative to said housing; filter bag means suspended from said second wall with its upper open end within said filter opening, said bag means being disposed in said filter chamber; and second resilient sealing means between said filter bag means and said second wall.

18. In a device of the character described, the combination of: a housing; a vertical partition in said housing defining a motor chamber on one side thereof and a filter chamber on the other side thereof; a first wall disposed in said motor chamber and having a motor opening therein; an electric motor unit in said motor chamber below said first wall; means for maintaining said motor unit in sealing engagement with said first wall; a second wall in said filter chamber and having a filter opening therein, said second wall being rigidly secured relative to said housing; filter bag means suspended from said second wall with its upper open end concentric with said filter opening, said bag means being disposed in said filter chamber below said second wall; and means for maintaining said upper end of said filter bag means in sealing engagement with said second wall.

19. In a device of the character described, the combination of: a housing; a vertical partition in said housing defining a motor chamber on one side thereof and a filter chamber on the other side thereof; a first wall disposed in said motor chamber and having a motor opening therein; an electric motor unit in said motor chamber below said first wall; a second wall in said filter chamber and having a filter opening therein; filter means disposed in said filter chamber below said second wall; an auxiliary motor mounted on said second wall and extending into said filter means and adapted to agitate the same; electrical connections adapted to connect said motors to a source of current; and switch means electrically connected to both of said motors and extending out of said housing so that selective operation of said motors may be controlled from the exterior of said housing.

20. In a device of the character described, the combination of: a housing; a vertical partition in said housing defining a motor chamber on one side thereof and a filter chamber on the other side thereof; a first wall disposed in said motor

chamber and having a motor opening therein; an electric motor unit in said motor chamber below said first wall; a second wall in said filter chamber and having a filter opening therein; filter means disposed in said filter chamber below said second wall; an auxiliary motor carried by said second wall within said filter opening, said auxiliary motor extending into said filter means and adapted to agitate the same; electrical connections adapted to connect said motors to a source of current; and switch means disposed in said motor chamber above said first wall and electrically connected to both of said motors and extending out of said housing so that selective operation of said motors may be controlled from the exterior of said housing.

21. In a motor chamber for a vacuum cleaner, the combination of: walls forming a motor housing, said housing walls being provided with an opening in a bottom wall thereof through which an electric motor can be inserted into said housing; a removable closure member attached to said housing so as to close said opening; an electric motor disposed in said motor housing above said closure member; a reel device in said motor housing interposed between said motor and said closure member, said reel device being adapted to support said motor on said closure member, said reel device being adapted to carry an electric cord for energizing said motor; and electrical connection means in said motor chamber electrically connecting said cord to said motor.

22. In a device of the character described, the combination of: a housing having an inlet opening and a discharge opening; filter means in said housing between said openings and adapted to filter solid particles from fluid passing therethrough between said openings; impelling means for drawing fluid into said housing through said inlet opening, causing such fluid to pass through said filter means, and to discharge it from said housing through said discharge opening; agitating means disposed wholly within and connected to said filter means and operable to agitate said filter means to dislodge such particles therefrom; and means for selectively operating but preventing simultaneous operation of said impelling means and said agitating means.

OTTO W. TIMM.

Certificate of Correction

April 11, 1950

Patent No. 2,503,568

OTTO W. TIMM

It is hereby certified that errors appear in the printed specification of the above numbered patent requiring correction as follows:

Column 4, line 22, for the word "opening" read *openings*; column 5, line 72, for "flange 66" read *flange 76*; column 13, line 30, strike out "bag" and insert the same after "filter", second occurrence, in line 29, same column; line 34, for "on" read *an*; line 51, after "said" insert *main*; column 18, line 19, after "housing" strike out "walls";

and that the said Letters Patent should be read with these corrections therein that the same may conform to the record of the case in the Patent Office.

Signed and sealed this 18th day of July, A. D. 1950.
